HEAD UNIT

This application claims priority to Japanese Patent Application No. 2016-191060 filed on Sep. 29, 2016. The entire disclosure of Japanese Patent Application No. 2016-191060 is hereby incorporated herein by reference.

BACKGROUND

1. Technical Field

The present invention relates to a head unit.

2. Related Art

A head unit (liquid ejecting head) which includes a driving IC and a plurality of piezoelectric elements provided correspondingly to each of a plurality of nozzles and ejects liquids from the plurality of nozzles by each of the plurality of piezoelectric elements being driven by a driving signal supplied from the driving IC is known.

In recent years, the head unit is manufactured by Micro Electro Mechanical Systems (MEMS) technology, and along with miniaturization of the head unit, a mounting method in which a driving IC and a substrate are joined by a resin core bump has been developed. In such a mounting method, unless a contact state between the driving IC and the substrate is appropriate, electrical connection between the driving IC and the substrate cannot be secured and an error occurs. For this reason, it is necessary to inspect conduction in a case of connecting the driving IC and the substrate by the resin core bump.

For example, in JP-A-2010-251392, a method in which when an IC chip on which a dummy terminal (dummy bump) is formed is mounted on a substrate, if the dummy terminal is pressed and is brought into contact with a pedestal unit of the substrate, a conductive film of the dummy terminal is divided so as to be in a non-conductive state, a probe (needle) is brought into contact with the conductive film of the dummy terminal, a resistance value is measured, and conduction is inspected based on the measured resistance value is disclosed.

By the way, in a head unit, since as nozzle rows become longer, more ejection can be performed in one operation and it is possible to increase a printing speed and as a distance between the nozzle rows becomes shorter, it is possible to reduce droplet landing deviation, and thus it is desirable that the head unit required to have high speed printing and high accuracy printing has a long shape in a nozzle row direction and has a short shape in a direction intersected with the nozzle row. As a result, there may be problems that a driving IC or a substrate to which the driving IC is connected has an elongated shape, a pitch of a plurality of resin core bumps provided correspondingly to a plurality of nozzles also becomes narrow, it is difficult to secure a space for bringing a probe into contact with the resin core bump, and fraction defective improves because normal inspection cannot be performed. Although it is possible to inspect conduction between the driving IC and the substrate by a method of JP-A-2010-251392, a bump disposition method in which even when a plurality of bumps are concentrated, electrical characteristics can be inspected by bringing the probe into contact (hereinafter, referred to as "probe inspection") is not disclosed in JP-A-2010-251392.

SUMMARY

An advantage of some aspects of the invention is that it provides a head unit in which a plurality of resin core bumps

2

connected to a driving IC and a substrate are disposed so as to enable probe inspection of the driving IC or the substrate.

The invention can be realized in the following aspects or application examples.

Application Example 1

According to this application example, there is provided a head unit including: a plurality of ejecting units that eject liquids; a driving IC that drives the plurality of ejecting units; a substrate; a first electrode group that includes a plurality of electrodes connected to the driving IC and the substrate; and a second electrode group that includes a plurality of electrodes connected to the driving IC and the substrate, in which the driving IC is a rectangular shape that has a first short side, a first long side, a second short side, and a second long side in plan view, at least a part of each of the plurality of electrodes included in the first electrode group and each of the plurality of electrodes included in the second electrode group is provided on a surface of a resin layer 10 extended in a direction from the first short side to the second short side, the plurality of electrodes included in the first electrode group are disposed in parallel in a direction from the first short side to the second short side along the first long side, the plurality of electrodes included in the second electrode group are disposed at positions closer to the first long side than the second long side and farther from the first long side than the plurality of electrodes included in the first electrode group, and for each of the plurality of electrodes included in the second electrode group, an imaginary straight line intersected with the electrode and the first long side and not intersected with any of the plurality of electrodes included in the first electrode group exists in plan view of the driving IC.

The substrate may be a relay substrate which relays a signal from the driving IC to the substrate on which at least 35 a part of an ejecting unit is formed and may be a substrate itself on which at least a part of the ejecting unit is formed.

According to the head unit of this application example, after the plurality of electrodes of the first electrode group and the plurality of electrodes of the second electrode group 40 are provided on the driving IC or the substrate, by bringing a probe into contact with each of the plurality of electrodes of the first electrode group and by bringing the probe into contact with each of the plurality of electrodes of the second electrode group disposed on an inside than the plurality of electrodes of the first electrode group along each of imaginary straight lines, probe inspection can be performed. Accordingly, it is possible to reduce fraction defective (improve yielding percentage) after completion of the head unit according to this application example and to realize cost 45 reduction of the head unit.

In addition, according to the head unit of this application example, since it is possible to give elasticity to the plurality of electrodes included in the first electrode group and the plurality of electrodes included in the second electrode 50 group by the resin layer, conduction between the driving IC and the substrate can be more reliable by the plurality of electrodes included in the first electrode group and the plurality of electrodes included in the second electrode group. Further, since it is possible to produce the plurality of electrodes and various types of wiring in a same process, it 55 is easier to manufacture the head unit according to this application example.

Application Example 2

According to this application example, there is provided a head unit including: a plurality of ejecting units that eject

liquids; a driving IC that drives the plurality of ejecting units; a substrate; a first electrode group that includes a plurality of electrodes connected to the driving IC and the substrate; and a second electrode group that includes a plurality of electrodes connected to the driving IC and the substrate, in which the driving IC is a rectangular shape that has a first short side, a first long side, a second short side, and a second long side in plan view, at least a part of each of the plurality of electrodes included in the first electrode group and each of the plurality of electrodes included in the second electrode group is provided on a surface of a resin layer extended in a direction from the first short side to the second short side, the plurality of electrodes included in the first electrode group are disposed in parallel in a direction from the first short side to the second short side along the first long side, the plurality of electrodes included in the second electrode group are disposed at positions closer to the first long side than the second long side and farther from the first long side than the plurality of electrodes included in the first electrode group, and a sum of areas of regions, not overlapped with any of the plurality of electrodes included in the first electrode group, of the plurality of electrodes included in the second electrode group is equal to or larger than a sum of areas of regions, overlapped with any of the plurality of electrodes included in the first electrode group, of the plurality of electrodes included in the second electrode group in plan view of the driving IC.

The substrate may be a relay substrate which relays a signal from the driving IC to the substrate on which at least a part of an ejecting unit is formed and may be a substrate itself on which at least a part of the ejecting unit is formed.

In other words, in the head unit according to this application example, since a proportion of parts of the plurality of electrodes included in the second electrode group which can be visually checked without being blocked by the plurality of electrodes included in the first electrode group from a side of the first long side of the driving IC is high, it is easy to bring the probe into contact with each of the plurality of electrodes included in the second electrode group. According to the head unit of this application example, after the plurality of electrodes of the first electrode group and the plurality of electrodes of the second electrode group are provided on the driving IC or the substrate, by bring a probe into contact with each of the plurality of electrodes of the first electrode group and by bring the probe into contact with each of the plurality of electrodes of the second electrode group disposed on an inside than the plurality of electrodes of the first electrode group, probe inspection can be performed.

In addition, according to the head unit of this application example, since it is possible to give elasticity to the plurality of electrodes include in the first electrode group and the plurality of electrodes included in the second electrode group by the resin layer, conduction between the driving IC and the substrate can be more reliable by the plurality of electrodes include in the first electrode group and the plurality of electrodes included in the second electrode group.

Application Example 3

In the head unit according to the application example, an output signal from the driving IC may be transmitted to the substrate via each of the plurality of electrodes included in the first electrode group, and an input signal to the driving

IC may be transmitted from the substrate via each of the plurality of electrodes included in the second electrode group.

Application Example 4

In the head unit according to the application example, the output signal from the driving IC may be a driving signal that drives each of the plurality of ejecting units.

According to the head unit of this application example, since the number of electrodes included in the first electrode group relatively easy to contact with the probe is large corresponding to the number of the ejecting units and the number of electrodes included in the second electrode group relatively not easy to contact with the probe is smaller than the number of the electrodes included in the first electrode group, it is possible to easily perform probe inspection of the driving IC or the substrate as compared with a case where the number of the electrodes included in the second electrode group is larger than the number of the electrodes included in the first electrode group.

Application Example 5

In the head unit according to the application example, the input signal to the driving IC may be an original signal of the driving signal.

In the head unit according to the application example, it is possible to perform probe inspection based on the original signal of the driving signal which greatly affects ejection accuracy by the ejecting unit.

Application Example 6

In the head unit according to the application example, the input signal to the driving IC may be a power supply voltage signal.

In the head unit according to the application example, it is possible to perform probe inspection based on the power supply voltage signal which is important for the driving IC so as to operate accurately.

Application Example 7

In the head unit according to the application example, a length of the first long side may be equal to or larger than 10 times a length of the first short side.

In the head unit according to the application example, since the driving IC is a considerably long elongated chip, a disposition region of the plurality of electrodes included in the first electrode group and the plurality of electrodes included in the second electrode group also becomes an elongated region. For this reason, a distance from the short side of the disposition region is too long and the probe does not reach a part of the electrode, and the probe is brought into contact with each of the electrodes from the long side. According to the head unit of the application example, it is possible to perform probe inspection of the driving IC or the substrate by bringing the probe into contact with each of the electrodes from a side corresponding to the first long side of the driving IC in the disposition region.

Application Example 8

In the head unit according to the application example, the plurality of electrodes included in the first electrode group

5

and the plurality of electrodes included in the second electrode group may be provided on a surface of the driving IC.

According to the head unit of the application example, it is possible to perform probe inspection of the driving IC by bringing the probe into contact with each of the electrodes from a side of the first long side of the driving IC.

Application Example 9

In the head unit according to the application example, the head unit may be used for an industrial ink jet printer.

“Industrial ink jet printer” means a printer (manufacturing apparatus) used for manufacturing an Organic Electro-Luminescence (OEL) device, a color filter for a liquid crystal, or the like by a droplet ejecting method. The industrial ink jet printer is mainly used for manufacturing industrial products such as a liquid crystal color filter and an organic electro-luminescence device, and the like and is required to have ejection weight accuracy, enlargement to improve productivity, downsizing for improvement in concentration of finished products (high resolution of an ejecting unit), or the like. For this reason, since density of nozzles is higher, the driving IC becomes longer, or, since the number of the nozzles becomes larger, the number of the driving ICs becomes larger, but by applying the head unit according to the application example, it is possible to perform probe inspection of the driving IC or the substrate, to improve yielding percentage, and to reduce the number of inspection processes.

Application Example 10

In the head unit according to the application example, the head unit may be used for a textile ink jet printer.

“Textile ink jet printer” means an ink jet printer which performs printing on a fabric or sublimates and transfers an image printed on a medium and performs printing on the fabric. The textile ink jet printer is mainly used for a purpose of producing small quantities of various types and high speed on-demand supply of products, and is used for providing fabrics in accordance with customer needs. For this reason, since density of nozzles is higher, the driving IC becomes longer, or, since the number of the nozzles becomes larger, the number of the driving ICs becomes larger, but by applying the head unit according to the application example, it is possible to perform probe inspection of the driving IC or the substrate, to improve yielding percentage, and to reduce the number of inspection processes.

Application Example 11

In the head unit according to the application example, the head unit may be used for a label ink jet printer.

“Label ink jet printer” means an ink jet printer which prints a receipt, a product label, a ticket, and the like. The label ink jet printer is mainly used in a supermarket cash register in cooperation with a Point Of Sales (POS) system, an airport counter, a factory which performs printing of a package label of grocery, and the like and is required to print large volumes of data of different format at high speed, to operate stably, and the like. For this reason, since density of nozzles is higher, the driving IC becomes longer, or, since the number of the nozzles becomes larger, the number of the driving ICs becomes larger, but by applying the head unit according to the application example, it is possible to

6

perform probe inspection of the driving IC or the substrate, to improve yielding percentage, and to reduce the number of inspection processes.

Application Example 12

In the head unit according to the application example, the head unit may be used for a business ink jet printer.

“Business ink jet printer” means an ink jet printer developed and designed on a premise of being used in an office or the like. The business ink jet printer is required to have the same printing speed (specifically, a printing speed of approximately 30 ppm (pages per minute) to 100 ppm) as that of an electrophotographic printing apparatus and to have a higher printing speed than that of a printer supplied for a traditional consumer market. For this reason, since density of nozzles is higher, the driving IC becomes longer, or, since the number of the nozzles becomes larger, the number of the driving ICs becomes larger, but by applying the head unit according to the application example, it is possible to perform probe inspection of the driving IC or the substrate, to improve yielding percentage, and to reduce the number of inspection processes.

BRIEF DESCRIPTION OF THE DRAWINGS

The invention will be described with reference to the accompanying drawings, wherein like numbers reference like elements.

FIG. 1 is a diagram illustrating a schematic configuration of an inside of a liquid ejecting apparatus.

FIG. 2 is a block diagram illustrating an electrical configuration of the liquid ejecting apparatus.

FIG. 3 is a diagram for explaining operation of a selection controller in a head unit.

FIG. 4 is a diagram illustrating a configuration of the selection controller in the head unit.

FIG. 5 is a diagram illustrating decoding contents of a decoder in the head unit.

FIG. 6 is a diagram illustrating a configuration of a selection unit in the head unit.

FIG. 7 is a diagram illustrating a driving signal selected by the selection unit.

FIG. 8 is a cross-sectional view for explaining an internal configuration of a head.

FIG. 9 is a literal view of a driving IC.

FIG. 10 is a plane view of a driving IC in Embodiment 1.

FIG. 11 is a diagram illustrating a form of probe inspection of the driving IC.

FIG. 12 is a diagram illustrating a form of probe inspection of the driving IC.

FIG. 13 is a plane view of a driving IC in Embodiment 2.

FIG. 14 is another plane view of the driving IC in Embodiment 2.

FIG. 15 is a schematic perspective view illustrating an example of a liquid ejecting apparatus as a textile ink jet printer.

FIG. 16 is a schematic perspective view illustrating an example of a liquid ejecting apparatus as a label ink jet printer.

FIG. 17 is a schematic perspective view illustrating an example of a liquid ejecting apparatus as an industrial ink jet printer.

DESCRIPTION OF EXEMPLARY EMBODIMENTS

Hereinafter, preferable embodiments of the invention will be described in detail with reference to drawings. The used

drawings are for convenience of explanation. The embodiments to be described below do not unfairly limit contents of the invention described in the claims. In addition, all of configurations to be described below are not essential components of the invention.

Hereinafter, a head unit according to the invention will be described by the head unit applied to a liquid ejecting apparatus which is a printing apparatus as an example.

1. Embodiment 1

1-1. Overall Liquid Ejecting Apparatus

FIG. 1 is a perspective view illustrating a schematic configuration of an inside of a liquid ejecting apparatus 1 (printing apparatus) to which the head unit of the present embodiment is applied. The liquid ejecting apparatus 1 is an ink jet printer which forms an ink dot group on a print medium such as paper by ejecting an ink according to image data supplied from an external host computer and prints an image (including letters, figures, and the like) according to the image data. In FIG. 1, a housing and a cover do not illustrated. As illustrated in FIG. 1, the liquid ejecting apparatus 1 includes a moving mechanism 3 which moves a head unit 2 in a main scanning direction (reciprocating motion).

The moving mechanism 3 has a carriage motor 31 which is a driving source of the head unit 2, a carriage guide shaft 32 of which both of ends are fixed, and a timing belt 33 which is expanded approximately in parallel with the carriage guide shaft 32 and is driven by the carriage motor 31.

The carriage 24 of the head unit 2 is configured to be able to mount a predetermined number of ink cartridges 22. For example, four cartridges 22 corresponding to four colors of yellow, cyan, magenta, and black are mounted on the carriage 24 and an ink of a color corresponding to each of the ink cartridges 22 is filled in the ink cartridge 22.

The carriage 24 is supported by the carriage guide shaft 32 to be freely reciprocated and is fixed to a part of the timing belt 33. For this reason, if the timing belt 33 is run in forward and reverse directions by the carriage motor 31, the head unit 2 is reciprocated while being guided by the carriage guide shaft 32. In this way, the carriage motor 31 is a motor which moves the carriage 24 in the main scanning direction (first direction).

In addition, the moving mechanism 3 includes a linear encoder 90 which detects a position of the head unit 2 in the main scanning direction. The position of the head unit 2 in the main scanning direction is detected by the linear encoder 90.

In addition, a head 20 (recording head) is provided on a portion of the head unit 2 facing a print medium P. As described below, the head 20 is a liquid ejecting head for ejecting ink drops (droplets) from a plurality of nozzles, and various control signals and the like are supplied to the head unit 2 via a flexible cable 190.

The liquid ejecting apparatus 1 includes a transport mechanism 4 which transports the print medium P on a platen 40 in a sub-scanning direction. The transport mechanism 4 includes a transport motor 41 which is a driving source and a transport roller 42 which is rotated by the transport motor 41 and transports the print medium P in the sub-scanning direction.

At a timing when the print medium P is transported by the transport mechanism 4, an image is formed on a surface of the print medium P by the head 20 ejecting an ink drop onto the print medium P.

A home position which is a base point of scanning of the head unit 2 is set to an end region within a movement range of the head unit 2. In the home position, a capping member 70 which seals a nozzle forming surface of the head 20 and a wiper member 71 which wipes the nozzle forming surface are disposed. The liquid ejecting apparatus 1 forms an image on a surface of the print medium P in both directions when the head unit 2 forward moves from the home position to an end on an opposite side and the head unit 2 backward returns from the end on the opposite side to the home position side.

A flushing box 72 which collects ink drops ejected from the head 20 when flushing operation is disposed in an end of the platen 40 in the main scanning direction. The flushing operation is operation of forcibly ejecting an ink from each of nozzles regardless of image data to be printed so as to prevent an appropriate amount of the ink from not being ejected by clogging the nozzle and bubbles entering into the nozzles due to thickening of the ink in a periphery of the nozzles. In detail, in a region (ink ejection region) other than a region in which an ink drop is ejected on the print medium P in the platen 40, in more detail, a region other than an outside than the ink ejection region in the main scanning direction, the flushing box 72 is disposed at a position which is an outside than an end of the print medium P in a width direction (maximum recording width) when the print medium P having a maximum size allowed by the liquid ejecting apparatus 1 is disposed on the platen 40. Although it is preferable that the flushing boxes 72 be provided on both sides of the platen 40 in the main scanning direction, the flushing box 72 may be provided at least on one side.

The head unit 2 moves above the print medium P or the flushing box 72 and performs operation of ejecting an ink drop toward the print medium P and flushing operation of ejecting an ink drop toward the flushing box 72.

1-2. Electrical Configuration of Liquid Ejecting Apparatus

FIG. 2 is a block diagram illustrating an electrical configuration of the liquid ejecting apparatus 1. As illustrated in FIG. 2, a control unit 10 and the head unit 2 are connected to the liquid ejecting apparatus 1 via the flexible cable 190.

The control unit 10 has a controller 100, a carriage motor driver 35, and a transport motor driver 45. Among the controller 100, the carriage motor driver 35, and the transport motor driver 45, the controller 100 outputs various control signals and the like for control of each of units when image data is supplied from a host computer.

In detail, the controller 100 recognizes a scanning position (current position) of the head unit 2 based on a detection signal (encoder pulse) of the linear encoder 90. Then, based on the scanning position of the head unit 2, the controller 100 supplies a control signal Ctr1 to the carriage motor driver 35 and the carriage motor driver 35 drives the carriage motor 31 according to the control signal Ctr1. Accordingly, a movement of the carriage 24 in the main scanning direction is controlled.

In addition, the controller 100 supplies a control signal Ctr2 to the transport motor driver 45 and the transport motor driver 45 drives the transport motor 41 according to the control signal Ctr2. Accordingly, a movement of the transport mechanism 4 in the sub-scanning direction is controlled.

In addition, the controller 100 supplies a clock signal Sck, a data signal Data, control signals LAT and CH, and digital data dA and dB to the head unit 2.

In addition, the controller 100 causes a maintenance unit 80 to execute a maintenance process of restoring an ejecting state of an ink in an ejecting unit 600 to a normal state. As the maintenance process, the maintenance unit 80 may have

a cleaning mechanism **81** for performing a cleaning process (pumping process) in which an ink, a bubble, and the like thickened inside the ejecting unit **600** are sucked by a tube pump (not illustrated). In addition, as the maintenance process, the maintenance unit **80** may have a wiping mechanism **82** for performing a wiping process in which foreign matters such as paper dust and the like adhering to a periphery of a nozzle of the ejecting unit **600** are wiped off by the wiper member **71**.

The head unit **2** has driving circuits **50-a** and **50-b** and the head **20**. In addition, the head **20** includes a plurality of ejecting units **600** which eject a liquid and a driving IC **200** which drives the plurality of ejecting units **600**. The driving IC **200** includes a selection controller **210** and a plurality of selection units **230**. In FIG. 2, only one driving IC **200** is illustrated, but the head unit **2** may have a plurality of driving ICs **200** which drive the plurality of ejecting units **600** different from each other. Hereinafter, for simplicity of explanation, it is assumed that there is only one driving IC **200**, but the following description can be easily expanded even in a case of the plurality of driving ICs **200**.

After the driving circuit **50-a** performs digital/analog conversion on the data **dA**, the driving circuit **50-a** generates a driving signal COM-A by Class D amplification and supplies the driving signal COM-A to each of the selection units **230**. In the same manner, after the driving circuit **50-b** performs digital/analog conversion on the data **dB**, the driving circuit **50-b** generates a driving signal COM-B by Class D amplification and supplies the driving signal COM-B to each of the selection units **230**. Here, the data **dA** defines a waveform of the driving signal COM-A and the data **dB** defines a waveform of the driving signal COM-B. Since input data and an output driving signal are different only, the driving circuits **50-a** and **50-b** may have the same circuit configuration.

The selection controller **210** instructs selection of one of the driving signals COM-A and COM-B for each of the selection units **230** (or non-selection) by the clock signal **Sck**, the data signal **Data**, and the control signals **LAT** and **CH** supplied from the controller **100**.

Each of the selection units **230** selects the driving signal COM-A or COM-B according to an instruction from the selection controller **210** and supplies the selected driving signal COM-A or COM-B to one end of each of piezoelectric elements **60** included in the head **20**. In FIG. 2, a voltage of the driving signal is denoted by **Vout**. A voltage **VBS** is supplied to the other end of each of the piezoelectric elements **60** in common.

The piezoelectric element **60** is displaced by applying the driving signal. The piezoelectric element **60** is provided in accordance with each of the plurality of ejecting units **600** in the head **20**. Then, the piezoelectric element **60** is displaced according to a difference between the driving signal voltage **Vout** selected by the selection unit **230** and the voltage **VBS** and ejects an ink. In this way, the driving signals COM-A or COM-B is an original signal of a driving signal (a driving signal selected by the selection unit **230**) which drives each of the plurality of ejecting units **600**.

FIG. 3 is a diagram illustrating waveforms and the like of the driving signals COM-A and COM-B. As illustrated in FIG. 3, the driving signal COM-A is a waveform obtained by continuing a trapezoidal waveform **Adp1** disposed in a period of time **T1** from an output (rising) of the control signal **LAT** to an output of the control signal **CH** within a print cycle **Ta** and a trapezoidal waveform **Adp2** disposed in

a period of time **T2** from an output of the control signal **CH** to an output of the next control signal **LAT** within a print cycle **Ta**.

In the present embodiment, the trapezoidal waveforms **Adp1** and **Adp2** are approximately equal to each other. If each of the trapezoidal waveforms **Adp1** and **Adp2** is supplied to one end of the piezoelectric element **60**, the trapezoidal waveforms **Adp1** and **Adp2** are waveforms in which a nozzle corresponding to each of the piezoelectric elements **60** ejects a predetermined amount, specifically, a moderate amount of ink.

The driving signal COM-B is a waveform obtained by continuing a trapezoidal waveform **Bdp1** disposed in the period of time **T1** and a trapezoidal waveform **Bdp2** disposed in the period of time **T2**. In the present embodiment, the trapezoidal waveforms **Bdp1** and **Bdp2** are different from each other. Among the trapezoidal waveforms **Bdp1** and **Bdp2**, the trapezoidal waveform **Bdp1** is a wave for preventing an ink in a periphery of an opening portion of a nozzle from being thickened by slightly vibrating the ink. For this reason, even if the trapezoidal waveform **Bdp1** is supplied to one end of the piezoelectric element **60**, an ink drop is not ejected from the nozzle corresponding to the piezoelectric element **60**. In addition, the trapezoidal waveform **Bdp2** is a waveform different from the trapezoidal waveform **Adp1** (**Adp2**). If the trapezoidal waveform **Bdp2** is supplied to one end of the piezoelectric element **60**, the trapezoidal waveform **Bdp2** is a waveform when an amount of ink smaller than the predetermined amount is ejected from the nozzle corresponding to the piezoelectric element **60**.

A voltage of the trapezoidal waveforms **Adp1**, **Adp2**, **Bdp1**, and **Bdp2** at start timing and a voltage at end timing are voltages **Vc** in common. That is, each of the trapezoidal waveforms **Adp1**, **Adp2**, **Bdp1**, and **Bdp2** is a waveform which starts at the voltage **Vc** and ends at the voltage **Vc**.

FIG. 4 is a diagram illustrating a configuration of the selection controller **210** in FIG. 2. As illustrated in FIG. 4, the clock signal **Sck**, the data signal **Data**, and the control signals **LAT** and **CH** are supplied from the control unit **10** to the selection controller **210**. A set of a shift register (S/R) **212**, a latch circuit **214**, and a decoder **216** is provided corresponding to each of the piezoelectric elements **60** (nozzles) in the selection controller **210**.

In forming one dot of an image, the data signal **Data** defines a size of the dot. In the present embodiment, in order to express 4 gradations of non-record, a small dot, a medium dot, and a large dot, the data signal **Data** is configured to include 2 bits of an upper bit (MSB) and a lower bit (LSB).

The data signal **Data** is supplied in serial from the controller **100** to each of nozzles in accordance with main scanning of the head unit **2** in synchronization with the clock signal **Sck**. The shift register **212** is configured to temporarily hold the data signal **Data** supplied in serial for 2 bits corresponding to the nozzle.

In detail, the shift registers **212** having the number of stages corresponding to the piezoelectric elements **60** (nozzles) are cascade-connected to each other, and the data signal **Data** supplied in serial is transferred to a sequentially next stage according to the clock signal **Sck**.

When it is assumed that the number of the piezoelectric elements **60** is **m** (**m** is plural), in order to distinguish the shift registers **212**, it is sequentially denoted as first stage, second stage, . . . , **m**-th stage from an upstream side to which the data signal **Data** is supplied.

The latch circuit **214** latches the data signal Data held by the shift register **212** at a rising edge of the control signal LAT.

The decoder **216** decodes the data signal Data of 2 bits latched by the latch circuit **214**, outputs selection signals Sa and Sb, and defines selection of the selection unit **230** for each of the periods of time T1 and T2 defined by the control signal LAT and the control signal CH.

FIG. 5 is a diagram illustrating decoding contents in the decoder **216**. In FIG. 5, the latched data signal Data of 2-bit is denoted as MSB and LSB. For example, when the data signal Data is (0, 1), the decoder **216** respectively outputs H and L levels in the period of time T1 and respectively outputs L and H levels in the period of time T2 as logical levels of the selection signals Sa and Sb.

The logical levels of the selection signals Sa and Sb are level-shifted to high amplitude logic than logic levels of the clock signal Sck, the data signal Data, the control signals LAT and CH by a level shifter (not illustrated).

FIG. 6 is a diagram illustrating a configuration of the selection unit **230** corresponding to one piezoelectric element **60** (nozzle) in FIG. 2.

As illustrated in FIG. 6, the selection unit **230** has inverters (not circuits) **232a** and **232b** and transfer gates **234a** and **234b**.

While the selection signal Sa from the decoder **216** is supplied to a positive control end, to which a circle is not attached, in the transfer gate **234a**, the selection signal Sa is logically inverted by the inverter **232a** and is supplied to a negative control end, to which a circle is attached, in the transfer gate **234a**. In the same manner, while the selection signal Sb is supplied to a positive control end in the transfer gate **234b**, the selection signal Sb is logically inverted by the inverter **232b** and is supplied to a negative control end in the transfer gate **234b**.

The driving signal COM-A is supplied to an input end of the transfer gate **234a** and the driving signal COM-B is supplied to an input end of the transfer gate **234b**. An output end of the transfer gate **234a** and an output end of the transfer gate **234b** are connected in common and are connected to one end of the corresponding piezoelectric element **60**.

When the selection signal Sa is an H level, the transfer gate **234a** conducts (ON) between the input end and the output end and when the selection signal Sa is an L level, the transfer gate **234a** non-conducts (OFF) between the input end and the output end. In the same manner, the transfer gate **234b** turns on and off between the input end and the output end according to the selection signal Sb.

Next, operation of the selection controller **210** and the selection unit **230** will be described with reference to FIG. 3.

The data signal Data is supplied in serial from the controller **100** to each of nozzles in synchronization with the clock signal Sck and is sequentially transferred by the shift register **212** corresponding to the nozzle. Then, if the controller **100** stops to supply the clock signal Sck, each of the shift registers **212** is in a state in which the data signal Data corresponding to the nozzle is held. The data signal Data is supplied in order of the last m-th stage, . . . , second stage, and first stage corresponding to nozzles in the shift registers **212**.

Here, when the control signal LAT rises, each of the latch circuits **214** simultaneously latch the data signal Data held by the shift register **212**. In FIG. 3, LT1, LT2, . . . , LTm illustrate that the data signal Data is latched by the latch

circuits **214** corresponding to the shift registers **212** of first stage, second stage, . . . , m-th stage.

The decoder **216** outputs logical levels of the selection signals Sa and Sb in each of the periods of time T1 and T2 as contents illustrated in FIG. 5 according to a size of a dot defined by the latched data signal Data.

That is, in a case where the data signal Data is (1, 1) and a size of a large dot is defined, the decoder **216** sets the selection signals Sa and Sb to H and L levels in the period of time T1 and sets the selection signals Sa and Sb to H and L levels in the period of time T2. In addition, in a case where the data signal Data is (0, 1) and a size of a medium dot is defined, the decoder **216** sets the selection signals Sa and Sb to H and L levels in the period of time T1 and sets the selection signals Sa and Sb to L and H levels in the period of time T2. Further, in a case where the data signal Data is (1, 0) and a size of a small dot is defined, the decoder **216** sets the selection signals Sa and Sb to L and L levels in the period of time T1 and sets the selection signals Sa and Sb to L and H levels in the period of time T2. In addition, in a case where the data signal Data is (0, 0) and non-record is defined, the decoder **216** sets the selection signals Sa and Sb to L and H levels in the period of time T1 and sets the selection signals Sa and Sb to L and L levels in the period of time T2.

FIG. 7 is a diagram illustrating a voltage waveform of a driving signal selected according to the data signal Data and supplied to one end of the piezoelectric element **60**.

When the data signal Data is (1, 1), the selection signals Sa and Sb become H and L levels in the period of time T1, so that the transfer gate **234a** is turned on and the transfer gate **234b** is turned off. For this reason, the trapezoidal waveform Adp1 of the driving signal COM-A is selected in the period of time T1. Since the selection signals Sa and Sb become H and L levels in the period of time T2, the selection unit **230** selects the trapezoidal waveform Adp2 of the driving signal COM-A.

In this way, when the trapezoidal waveform Adp1 is selected and supplied to one end of the piezoelectric element **60** as a driving signal in the period of time T1, and the trapezoidal waveform Adp2 is selected and supplied to one end of the piezoelectric element **60** as the driving signal in the period of time T2, a moderate amount of ink is ejected two times from a nozzle corresponding to the piezoelectric element **60**. For this reason, inks are respective landed on the print medium P and combined, and as a result, a large dot as defined by the data signal Data is formed.

When the data signal Data is (0, 1), the selection signals Sa and Sb become H and L levels in the period of time T1, so that the transfer gate **234a** is turned on and the transfer gate **234b** is turned off. For this reason, the trapezoidal waveform Adp1 of the driving signal COM-A is selected in the period of time T1. Next, since the selection signals Sa and Sb become L and H levels in the period of time T2, the trapezoidal waveform Bdp2 of the driving signal COM-B is selected.

Accordingly, a moderate amount of ink and a small amount of ink are ejected two times from a nozzle. For this reason, inks are respective landed on the print medium P and combined, and as a result, a medium dot as defined by the data signal Data is formed.

When the data signal Data is (1, 0), the selection signals Sa and Sb become L and L levels in the period of time T1, so that the transfer gate **234a** is turned off and the transfer gate **234b** is turned off. For this reason, none of the trapezoidal waveforms Adp1 and Bdp1 is selected in the period of time T1. In a case where the transfer gates **234a** and **234b**

are both turned off, a path from a connection point between the output ends of the transfer gates **234a** and **234b** to one end of the piezoelectric element **60** is in a high impedance state in which none of portions is electrically connected. However, the piezoelectric element **60** holds a voltage (Vc-VBS) immediately before the transfer gates **234a** and **234b** are turned off by capacitive property of the piezoelectric element **60**.

Next, since the selection signals **Sa** and **Sb** become **L** and **H** levels in the period of time **T2**, the trapezoidal waveform **Bdp2** of the driving signal **COM-B** is selected. For this reason, since only a small amount of ink is ejected from the nozzle in the period of time **T2**, a small dot as defined by the data signal **Data** is formed on the print medium **P**.

When the data signal **Data** is **(0, 0)**, the selection signals **Sa** and **Sb** become **L** and **H** levels in the period of time **T1**, so that the transfer gate **234a** is turned off and the transfer gate **234b** is turned on. For this reason, the trapezoidal waveform **Bdp1** of the driving signal **COM-B** is selected in the period of time **T1**. Next, since the selection signals **Sa** and **Sb** become **L** and **L** levels in the period of time **T2**, none of the trapezoidal waveforms **Adp2** and **Bdp2** is selected.

For this reason, in the period of time **T1**, since an ink in a periphery of an opening portion of the nozzle vibrates only slightly and the ink is not ejected, as a result, a dot is not formed, that is, non-record is performed as defined by the data signal **Data**.

In this way, the selection unit **230** selects the driving signals **COM-A** or **COM-B** (or does not select) according to an instruction by the selection controller **210** and supplies the selected driving signals **COM-A** or **COM-B** to one end of the piezoelectric element **60**. For this reason, each of the piezoelectric elements **60** is driven according to a size of a dot defined by the data signal **Data**.

The driving signals **COM-A** and **COM-B** illustrated in FIG. 3 are merely examples. Actually, various combinations of waveforms prepared in advance are used according to a moving speed of the head unit **2**, properties of the print medium **P**, and the like.

1-3. Internal Configuration of Head

FIG. 8 is a cross-sectional view for explaining an internal configuration of the head **20**. In FIG. 8, right and left direction is a main scanning direction. As illustrated in FIG. 8, the head **20** of the present embodiment is attached to a head case **116** in a state in which an electronic device **114** and a flow path unit **115** are stacked. For convenience, a stacking direction of each of members will be described as an up-down direction.

A reservoir **118** which supplies an ink to each of pressure chambers (cavities) **130** is formed inside the head case **116**. The reservoir **118** is a space in which an ink common to a plurality of juxtaposed pressure chambers **130** is stored and two reservoirs **118** are formed corresponding to rows of the pressure chambers **130** juxtaposed in two rows. An ink introduction path (not illustrated) for introducing an ink from an ink cartridge **22** side into the reservoir **118** is formed above the head case **116**. In addition, an accommodating space **117** in which the electronic device **114** (driving IC **200**, pressure chamber forming substrate **129**, sealing plate **160**, and the like) stacked on a communication substrate **124** is accommodated is formed on a lower surface side of the head case **116**.

The flow path unit **115** has the communication substrate **124** and a nozzle plate **121**. A common liquid chamber **125** which communicates with the reservoir **118** and stores an ink common to each of the pressure chambers **130** and an individual communication path **126** which individually sup-

plies the ink from the reservoir **118** to each of the pressure chambers **130** via the common liquid chamber **125** are formed on the communication substrate **124**. The common liquid chamber **125** is an elongated empty portion along a nozzle row direction and two rows of the common liquid chambers **125** are formed corresponding to rows of the pressure chambers **130** juxtaposed in two rows. The individual communication paths **126** are plurally formed along a juxtapositional direction of the pressure chamber **130** in accordance with the pressure chamber **130** in a thin plate portion of the common liquid chamber **125**. The individual communication path **126** communicates with an end of one side of the corresponding pressure chamber **130** in a longitudinal direction in a state in which the communication substrate **124** and the pressure chamber forming substrate **129** are joined.

In addition, a nozzle communication path **127** penetrating through the communication substrate **124** in a substrate thickness direction is formed at a position corresponding to each of nozzles **122** of the communication substrate **124**. That is, the nozzle communication paths **127** are plurally formed along the nozzle row direction corresponding to nozzle rows. By the nozzle communication path **127**, the pressure chamber **130** communicates with the nozzle **122**. The nozzle communication path **127** communicates with an end of the other side (opposite side of individual communication path **126**) of the corresponding pressure chamber **130** in a longitudinal direction in a state in which the communication substrate **124** and the pressure chamber forming substrate **129** are joined.

The nozzle plate **121** is a substrate joined to a lower surface (a surface opposite to the pressure chamber forming substrate **129**) of the communication substrate **124**. By the nozzle plate **121**, an opening on a lower surface side of a space which is the common liquid chamber **125** is sealed. In addition, in the nozzle plate **121**, a plurality of nozzles **122** are formed linearly (in a row shape) and two rows of the nozzles **122** are formed corresponding to rows of the pressure chambers **130** formed in two rows. The plurality of juxtaposed nozzles **122** (nozzle rows) are provided at a pitch (for example, 600 dpi) corresponding to dot formation density from one end side of the nozzle **122** to the other end side of the nozzle **122** and at an interval along the substrate **124** direction orthogonal to the main scanning direction.

The electronic device **114** is a thin plate type device which functions as an actuator for generating pressure fluctuation in an ink in each of the pressure chambers **130**. In the electronic device **114**, the pressure chamber forming substrate **129**, a diaphragm **131**, the piezoelectric element **60**, the sealing plate **160**, and the driving IC **200** are stacked to form a unit.

In the pressure chamber forming substrate **129**, spaces to be the pressure chambers **130** are plurally juxtaposed along the nozzle row direction. The space, of which a lower side is partitioned by the communication substrate **124** and an upper side is partitioned by the diaphragm **131**, constitutes the pressure chamber **130**. The pressure chambers **130** are formed in two rows corresponding to rows of the nozzles formed in two rows. Each of the pressure chambers **130** is an elongated empty portion in a direction orthogonal to the nozzle row direction and the individual communication path **126** communicates with an end of one side of the pressure chamber **130** in a longitudinal direction and the nozzle communication path **127** communicates with an end of the other side of the pressure chamber **130**.

The diaphragm 131 is a thin film type member having elasticity and is stacked on an upper surface (a surface opposite to a communication substrate 124 side) of the pressure chamber forming substrate 129. By the diaphragm 131, an upper opening of a space to be the pressure chamber 130 is sealed. A portion of the diaphragm 131 corresponding to an upper opening of the pressure chamber 130 functions as a displacement unit which is displaced in a direction away from or close to the nozzle 122 in accordance with flexure deformation of the piezoelectric element 60. That is, a region of the diaphragm 131 corresponding to the upper opening of the pressure chamber 130 is a driving region 135 in which flexure deformation is allowed. On the other hand, a region deviated from the upper opening of the pressure chamber 130 in the diaphragm 131 is a non-driving region 136 in which flexure deformation is inhibited.

Each of the piezoelectric elements 60 are stacked on the driving region 135. The piezoelectric elements 60 are formed along the nozzle row direction in two rows corresponding to the pressure chambers 130 juxtaposed along the nozzle row direction in two rows. For example, the piezoelectric element 60 includes a lower electrode layer 137 (individual electrode), a piezoelectric layer 138, and an upper electrode layer 139 (common electrode) sequentially stacked on the diaphragm 131. If an electric field is applied according to a potential difference of both electrodes between the lower electrode layer 137 and the upper electrode layer 139, the piezoelectric element 60 having such the configuration is deformed to be bent in a direction away from or close to the nozzle 122. An end on the other side (an outside of the piezoelectric element 60 in a longitudinal direction) of the lower electrode layer 137 extends beyond the region in which the piezoelectric layer 138 is stacked from the driving region 135, to the non-driving region 136. On the other hand, an end on one side (an inside of the piezoelectric element 60 in the longitudinal direction) of the upper electrode layer 139 extends beyond the region in which the piezoelectric layer 138 is stacked from the driving region 135, to the non-driving region 136 between rows of the piezoelectric elements 60.

The sealing plate 160 is a flat plate type substrate disposed with a space from the diaphragm 131 (or the piezoelectric element 60). The driving IC 200 driving the piezoelectric element 60 is disposed on a second surface 142 (upper surface) on an opposite side of a first surface 141 (lower surface) which is a surface on a diaphragm 131 side of the sealing plate 160. That is, the diaphragm 131 in which the piezoelectric element 60 is stacked is connected to the first surface 141 of the sealing plate 160 and the driving IC 200 is connected to the second surface 142.

A plurality of bump electrodes 140 which output a driving signal from the driving IC 200 to a piezoelectric element 60 side are formed on the first surface 141 of the sealing plate 160. The bump electrodes 140 are plurally formed respectively along a nozzle row direction on a position corresponding to one side of the lower electrode layer 137 (individual electrode) extended to an outside of one side of the piezoelectric element 60, on a position corresponding to the other side of the lower electrode layer 137 (individual electrode) extended to an outside of the other side of the piezoelectric element 60, and on a position corresponding to the upper electrode layer 139 (common electrode) common to a plurality of the piezoelectric elements 60 formed between rows of both side of the piezoelectric element 60. Then, each of the bump electrodes 140 is connected to the corresponding lower electrode layer 137 and upper electrode layer 139.

At least a part of the bump electrode 140 is provided on a surface of a resin layer 148 having elasticity. The resin layer 148 is formed as a ridge along the nozzle row direction on the first surface 141 of the sealing plate 160. The bump electrodes 140 conducted to the lower electrode layer 137 (individual electrode) are plurally formed along a nozzle row direction corresponding to the piezoelectric element 60 juxtaposed along the nozzle row direction. Each of the bump electrodes 140 extends from above the resin layer 148 to a piezoelectric element 60 side or an opposite side to the piezoelectric element 60 side to become a lower surface side wiring 147. Then, an end on a side opposite to the bump electrode 140 of the lower surface side wiring 147 is connected to a through-wiring 145.

The bump electrodes 140 corresponding to the upper electrode layer 139 are plurally formed on a lower surface side embedded wiring 151 embedded in the first surface 141 of the sealing plate 160, along a nozzle row direction. Then, the bump electrode 140 protrudes from above the resin layer 148 to both sides of the resin layer 148 in a width direction to form the lower surface side wiring 147 and is formed to conduct with the lower surface side embedded wiring 151. The bump electrodes 140 are plurally formed along a nozzle row direction.

The sealing plate 160 and the pressure chamber forming substrate 129 are joined by a photosensitive adhesive 143 in a state in which the bump electrode 140 is interposed therebetween. The photosensitive adhesive 143 is formed on both sides of each of the bump electrodes 140 in a direction orthogonal to a nozzle row direction. In addition, each of the photosensitive adhesives 143 is formed in a band shape along a nozzle row direction in a state of being separated from the bump electrode 140.

A plurality of upper surface side embedded wirings 150 extended in a nozzle row direction are formed on a region other than both of end sides in the second surface 142 of the sealing plate 160. Various power supply voltage signals, the driving signals COM-A and COM-B, and the like are supplied from a flexible printed substrate (not illustrated in FIG. 8) to the upper surface side embedded wiring 150.

Further, a plurality of electrodes 153 to which an output signal (driving signal) is input from the driving IC 200 are formed on regions on both end sides in the second surface 142 of the sealing plate 160. Each of the electrodes 153 is connected to the corresponding lower surface side wiring 147 via the through-wiring 145.

The through-wiring 145 is a wiring which relays between the first surface 141 and the second surface 142 of the sealing plate 160. By the through-wiring 145, the electrode 153 is electrically connected to the lower surface side wiring 147 extended from the bump electrode 140 corresponding to the electrode 153 and a driving signal is transmitted from the driving IC 200 to the pressure chamber forming substrate 129. In this way, the sealing plate 160 functions as a relay substrate which relays a driving signal from the driving IC 200 to the pressure chamber forming substrate 129.

The driving IC 200 is an IC chip for driving the piezoelectric element 60 and is stacked on the second surface 142 of the sealing plate 160 via an adhesive 159. A plurality of bump electrodes 252 are formed along a nozzle row direction on a region other than both of end sides in a surface on a sealing plate 160 side of the driving IC 200. At least a part of the bump electrode 252 is provided on a surface of a resin layer 253 having elasticity. The resin layer 253 is formed as a ridge along the nozzle row direction on the sealing plate 160 side of the driving IC 200. In addition, input terminals (not illustrated) connected to each of the bump electrodes

252 are plurally formed on a surface on the sealing plate 160 side of the driving IC 200 and a signal (various power supply voltage signals, the driving signals COM-A and COM-B, or the like) is transmitted from the upper surface side embedded wiring 150 provided on the sealing plate 160 to each of the input terminals via the bump electrode 252.

Further, a plurality of bump electrodes 250 connected to each of the electrodes 153 formed on the second surface 142 of the sealing plate 160 are plurally formed on regions on both of end sides in a surface on the sealing plate 160 side of the driving IC 200. At least a part of the bump electrode 250 is provided on a surface of a resin layer 251 having elasticity. The resin layer 251 is formed as a ridge along the nozzle row direction on the sealing plate 160 side of the driving IC 200. In addition, output terminals (not illustrated) connected to each of the bump electrodes 250 are plurally formed on a surface on the sealing plate 160 side of the driving IC 200 and a signal (individual driving signal for driving each of the piezoelectric elements 60) from each of the output terminals is transmitted to each of the bump electrodes 250.

The driving IC 200 is a considerably long chip in a nozzle row direction, and each of signals transmitted to each of the input terminals is transmitted through a wiring with a small thickness and width and considerably long length in an inside of the driving IC 200 and is supplied to each of the selection units 230 (see FIG. 2) which outputs an individual driving signal for driving each of the piezoelectric elements 60. For this reason, a resistance value between both ends of each of internal wirings of the driving IC 200 is considerably large and each of signals transmitted through each of the internal wirings is attenuated (voltage level decreases) under influence of voltage drop due to the wiring resistance, as a result, the signal becomes lower for the selection unit 230 close to an end. Therefore, in the present embodiment, the upper surface side embedded wiring 150 of which a thickness and a width are sufficiently larger than the internal wiring of the driving IC 200 is also used as a reinforcement wiring of each of the internal wirings of the driving IC 200. That is, each of the upper surface side embedded wirings 150 is provided in parallel with each of the internal wirings of the driving IC 200, and each of signals is transmitted to each of input terminals of the driving IC 200 via each of the upper surface side embedded wirings 150 and a plurality of bump electrodes 252 connected to each of the upper surface side embedded wirings 150. Accordingly, voltage drop of each of the signals supplied to each of the selection units 230 is reduced, and the selection unit 230 close to an end of the driving IC 200 is also less likely to perform malfunction.

The bump electrodes 250 are formed in two rows on both sides of the bump electrode 252 corresponding to rows of the piezoelectric element 60 juxtaposed in two rows, and in the rows of the bump electrodes 250, a distance (that is, a pitch) (a pitch of the output terminals of the driving IC 200) between centers of the bump electrodes 250 adjacent to each other is formed to be smaller than a pitch of the bump electrodes 140 (a pitch of the nozzles 122). That is, the sealing plate 160 also absorbs a difference between the pitch of the output terminals of the driving IC 200 and the pitch of the nozzles 122, accordingly, it is possible to miniaturize the driving IC 200.

The head 20 formed as described above introduces an ink from the ink cartridge 22 to the pressure chamber 130 via an ink introduction path, the reservoir 118, the common liquid chamber 125, and the individual communication path 126. In this state, by supplying a driving signal from the driving IC 200 to the piezoelectric element 60 via each of the bump

electrodes 250 and each of the electrodes 153 and each of wirings formed on the sealing plate 160, the piezoelectric element 60 is driven to cause pressure fluctuation in the pressure chamber 130. By using the pressure fluctuation, the head 20 ejects an ink drop from the nozzle 122 via the nozzle communication path 127.

The ejecting unit 600 is configured to include the piezoelectric element 60, the diaphragm 131, the pressure chamber 130, the individual communication path 126, the nozzle communication path 127, and the nozzle 122 (see FIG. 2). 1-4. Probe Inspection of Driving IC

In order to reduce fraction defective (improve yielding percentage) of the head unit 2, after the plurality of bump electrodes 250 and the plurality of bump electrodes 252 are formed on the driving IC 200, it is desirable to inspect electrical characteristics of the driving IC 200 by bringing a probe into contact with all of the bump electrodes 250 and the bump electrodes 252 before connection with the sealing plate 160. However, if the nozzle 122 advances in density and the driving IC 200 becomes a considerably long chip correspondingly, a disposition region of the bump electrode 250 and the bump electrode 252 becomes an elongated region. For this reason, a distance from a short side (a short side of the driving IC 200) of the disposition region is too long and a probe does not reach a part of the bump electrodes 252, and the bump electrode 250 disposed at a small pitch may cause an obstacle from a long side, so that the probe cannot be brought into contact with a part of the bump electrodes 252.

Therefore, in the present embodiment, in consideration of probe inspection of the driving IC 200, disposition of the bump electrodes 252 is devised, and the disposition of the bump electrodes 252 will be described below in detail with reference to FIGS. 9 and 10. FIG. 9 is a literal view (as viewed from a long side direction of the driving IC 200) of the driving IC 200 and FIG. 10 is a plane view (as viewed from a lower surface of FIG. 9) of the driving IC 200. In FIGS. 9 and 10, a bump electrode 250a and a bump electrode 250b correspond to the bump electrode 250 illustrated in FIG. 8 and a bump electrode 252a and a bump electrode 252b correspond to the bump electrode 252 illustrated in FIG. 8.

As illustrated in FIGS. 9 and 10, in plan view, the driving IC 200 may be a rectangular shape having a short side 201 (an example of “first short side” or “second short side”), a long side 202 (an example of “first long side”), a short side 203 (an example of “second short side” or “first short side”), and a long side 204 (an example of “second long side”). The driving IC 200 may be an elongated chip in which a length of the long side 202 is equal to or more than 10 times a length of the short side 201.

At least a part of each of a plurality of bump electrodes 250a is provided on a surface of the resin layer 251 extended in a direction from the short side 201 of the driving IC 200 to the short side 203. The plurality of bump electrodes 250a are disposed in parallel along the long side 202 of the driving IC 200 in the direction from the short side 201 to the short side 203. An electrode group 255 (an example of “first electrode group”) is configured to have the plurality of bump electrodes 250a. The plurality of bump electrodes 250a included in the electrode group 255 are connected to the driving IC 200 and the sealing plate 160 (an example of a substrate) and transmits an output signal (a driving signal for driving each of the plurality of ejecting units 600) from the driving IC 200 to the sealing plate 160 via each of the plurality of bump electrodes 250a.

In addition, at least a part of each of a plurality of bump electrodes 252a is provided on a surface of the resin layer 253 extended in a direction from the short side 201 of the driving IC 200 to the short side 203. The plurality of bump electrodes 252a are disposed at a position closer to the long side 202 than the long side 204 of the driving IC 200 and farther from the long side 202 than the plurality of bump electrodes 250a included in the electrode group 255. An electrode group 256 (an example of "second electrode group") is configured to have the plurality of bump electrodes 252a. The plurality of bump electrodes 252a included in the electrode group 256 are connected to the driving IC 200 and the sealing plate 160 and transmits an input signal (one of various power supply voltage signals, the driving signals COM-A and COM-B, and the like) to the driving IC 200 from the sealing plate 160 via each of the plurality of bump electrodes 252a.

In addition, at least a part of each of a plurality of bump electrodes 250b is provided on a surface of the resin layer 251 extended in a direction from the short side 201 of the driving IC 200 to the short side 203. The plurality of bump electrodes 250b are disposed in parallel along the long side 204 of the driving IC 200 in the direction from the short side 201 to the short side 203. An electrode group 257 (an example of "first electrode group") is configured to have the plurality of bump electrodes 250b. The plurality of bump electrodes 250b included in the electrode group 257 are connected to the driving IC 200 and the sealing plate 160 and transmits an output signal (a driving signal for driving each of the plurality of ejecting units 600) from the driving IC 200 to the sealing plate 160 via each of the plurality of bump electrodes 250b.

In addition, at least a part of each of a plurality of bump electrodes 252b is provided on a surface of the resin layer 253 extended in a direction from the short side 201 of the driving IC 200 to the short side 203. The plurality of bump electrodes 252b are disposed at a position closer to the long side 204 than the long side 202 of the driving IC 200 and farther from the long side 204 than the plurality of bump electrodes 250b included in the electrode group 257. An electrode group 258 (an example of "second electrode group") is configured to have the plurality of bump electrodes 252b. The plurality of bump electrodes 252b included in the electrode group 258 are connected to the driving IC 200 and the sealing plate 160 and transmits an input signal (one of various power supply voltage signals, the driving signals COM-A and COM-B, and the like) to the driving IC 200 from the sealing plate 160 via each of the plurality of bump electrodes 252b.

In the present embodiment, the resin layer 251 and the resin layer 253 are formed on the driving IC 200 and the bump electrodes 250a, 250b, 252a, and 252b are provided on a surface of the driving IC 200. Then, since at least parts of the bump electrodes 250a, 250b, 252a, and 252b are provided on a surface of the resin layer 251 or the resin layer 253, the bump electrodes 250a, 250b, 252a, and 252b have a rounded shape along a shape of the resin layer 251 or the resin layer 253. Accordingly, for probe inspection, in order to reliably bring a probe into contact with the bump electrodes 250a, 250b, 252a, and 252b, it is desirable to bring the probe into contact with the bump electrodes 250a, 250b, 252a, and 252b from a direction along a roundness (a long side 202 side or a long side 204 side of the driving IC 200). Especially, since the bump electrode 250a and the bump electrode 252a are closer to the long side 202 than the long side 204, it is desirable to bring the probe into contact with the bump electrode 250a and the bump electrode 252a from

the long side 202 side. Since the bump electrode 250b and the bump electrode 252b are closer to the long side 204 than the long side 202, it is desirable to bring the probe into contact with the bump electrode 250b and the bump electrode 252b from the long side 204 side. However, if the nozzle 122 advances in density and a pitch of the bump electrodes 250 (250a and 250b) correspondingly decreases, the bump electrode 250 (250a and 250b) may become an obstacle and the probe may not be brought into contact with a part of the bump electrodes 252 (252a and 252b).

Therefore, in the present embodiment, in consideration of a direction in which the probe are brought into contact, as illustrated in FIG. 10, in plan view of the driving IC 200, for each of the plurality of bump electrodes 252a included in the electrode group 256, the plurality of bump electrodes 252a are disposed so that an imaginary straight line 262a intersected with the bump electrode 252a and the long side 202 and not intersected with any of the plurality of bump electrodes 250a included in the electrode group 255 exists (imaginary straight line 262a can be drawn). In the same manner, in plan view of the driving IC 200, for each of the plurality of bump electrodes 252b included in the electrode group 258, the plurality of bump electrodes 252b are disposed so that an imaginary straight line 262b intersected with the bump electrode 252b and the long side 204 and not intersected with any of the plurality of bump electrodes 250b included in the electrode group 257 exists (imaginary straight line 262b can be drawn). Then, in an example of FIG. 10, in plan view of the driving IC 200, the imaginary straight line 262a for each of the bump electrodes 252a is not intersected with any other of the bump electrode 252a and any other of the imaginary straight line 262a, and the imaginary straight line 262b for each of the bump electrodes 252b is not intersected with any other of the bump electrode 252b and any other of the imaginary straight line 262b.

According to such a disposition, the probe can be brought into contact with all of the bump electrodes 252a constituting the electrode group 256 along the imaginary straight line 262a from the long side 202 side of the driving IC 200 and can be brought into contact with all of the bump electrodes 252b constituting the electrode group 258 along the imaginary straight line 262b from the long side 204 side of the driving IC 200.

FIGS. 11 and 12 are diagrams illustrating forms of probe inspection of the driving IC 200. FIG. 11 is a plane view (as viewed from a lower surface in FIG. 9) of the driving IC 200 and FIG. 12 is a lateral view (as viewed from a short side 201 side of the driving IC 200) of the driving IC 200. As illustrated in FIGS. 11 and 12, an inspection device can perform probe inspection so that probes 701, 702, and 703 are brought into contact from the long side 202 side of the driving IC 200 to the bump electrode 250a or the bump electrode 252a and probes 704, 705, and 706 are brought into contact from the long side 204 side of the driving IC 200 to the bump electrode 250b or the bump electrode 252b.

1-5. Operational Effect

As described above, in the head unit 2 of Embodiment 1, since the driving IC 200 is a considerably long elongated chip and the bump electrodes 250 and 252 are formed in a rounded shape, it is necessary to bring the probe into contact from the long side 202 and 204 sides of the driving IC 200 to each of the bump electrodes 250 and 252. According to the head unit 2 of Embodiment 1, after the bump electrodes 250 and 252 are provided on the driving IC 200, probe inspection of the driving IC 200 can be performed by bringing the probe into contact with each of the bump electrodes 250 and 252 and by bringing the probe into contact with each of the bump

electrodes 252 disposed on an inside than the bump electrodes 250 along the imaginary straight line described above. For example, it is possible to perform probe inspection based on a power supply voltage signal which is important for the driving IC 200 so as to operate accurately and the driving signals COM-A and COM-B which greatly affects ejection accuracy by the ejecting unit 600. Accordingly, since it is possible to detect an operation error of the driving IC 200 and a connection error of the bump electrodes 250 and 252 before completion of the head unit 2 of Embodiment 1, it is possible to reduce fraction defective (improve yielding percentage) after completion of the head unit 2 and to realize cost reduction of the head unit 2.

In addition, in the head unit 2 of Embodiment 1, the bump electrodes 250 which transmit a driving signal for driving each of the plurality of ejecting units 600 are disposed in parallel along the long sides 202 and 204 of the driving IC 200. According to the head unit 2 of the present embodiment, in a case where the number of the bump electrode 250 close to a long side of the driving IC 200 and easy to contact with the probe is large corresponding to the number of the ejecting unit 600 and is smaller than the number of the bump electrode 252 far from the long side of the driving IC 200 and not easy to contact with the probe, it is possible to easily perform probe inspection of the driving IC 200 as compared with a case where the number of the bump electrode 252 is larger than the number of the bump electrode 250.

In addition, according to the head unit 2 of Embodiment 1, since at least a part of each of the bump electrodes 250 and 252 is provided on a surface of the resin layers 251 and 253, it is possible to give elasticity to the bump electrodes 250 and 252 and to more reliably conduct with the driving IC 200 and the sealing plate 160 by the bump electrodes 250 and 252.

Although in the liquid ejecting apparatus 1 (ink jet printer) required to have high speed printing and high accuracy printing, since density of nozzles is higher, the driving IC 200 becomes longer, or, since the number of the nozzles becomes larger, the number of the driving ICs 200 becomes larger, by applying the head unit 2 of the present embodiment, it is possible to perform probe inspection of the driving IC 200, to improve yielding percentage, and to reduce the number of inspection processes. For example, the head unit 2 of Embodiment 1 may be used for a business ink jet printer developed and designed on a premise of being used in an office or the like. The business ink jet printer is required to have a printing speed (specifically, a printing speed of approximately 30 ppm (pages per minute) to 100 ppm) as an electrophotographic printing apparatus and to have a high printing speed than a printer supplied for a traditional consumer market. In addition, the business ink jet printer is required to have high durability and maintainability which can be repaired even if the business ink jet printer breaks down so as to be able to endure hard use in the office.

2. Embodiment 2

The head unit 2 of Embodiment 2 has the same configuration as that of Embodiment 1 except that disposition of the bump electrodes 252 is different. Hereinafter, the same description as Embodiment 1 will be omitted or simplified, and contents different from Embodiment 1 will be mainly described.

FIG. 13 is a plane view (as viewed from a lower surface of FIG. 9) of the driving IC 200 included in the head unit 2 of Embodiment 2. In the same manner as FIG. 10, in FIG. 13, a bump electrode 250a and a bump electrode 250b

correspond to the bump electrode 250 illustrated in FIG. 8 and a bump electrode 252a and a bump electrode 252b correspond to the bump electrode 252 illustrated in FIG. 8.

As illustrated in FIG. 13, for each of the plurality of bump electrodes 252a included in the electrode group 256, in plan view of the driving IC 200, if in a direction from the short side 201 to the short side 203, a region not overlapped with any of the plurality of bump electrodes 250a included in the electrode group 255 is R1 and a region overlapped with any of the plurality of bump electrodes 250a included in the electrode group 255 is R2, the plurality of bump electrodes 252a are disposed so that a sum of areas of the regions R1 is equal to or larger than a sum of areas of the regions R2. In the same manner, for each of the plurality of bump electrodes 252b included in the electrode group 258, in plan view of the driving IC 200, if in a direction from the short side 201 to the short side 203, a region not overlapped with any of the plurality of bump electrodes 250b included in the electrode group 257 is R3 and a region overlapped with any of the plurality of bump electrodes 250b included in the electrode group 257 is R4, the plurality of bump electrodes 252b are disposed so that a sum of areas of the regions R3 is equal to or larger than a sum of areas of the regions R4.

In other words, when the driving IC 200 is viewed from the long side 202 side in a side view, the plurality of bump electrodes 252a are disposed so that a sum of areas of regions, not overlapped with any of the plurality of bump electrodes 250a included in the electrode group 255, of the plurality of bump electrodes 252a included in the electrode group 256 is equal to or larger than a sum of areas of regions, overlapped with any of the plurality of bump electrodes 250a included in the electrode group 255, of the plurality of bump electrodes 252a included in the electrode group 256. In the same manner, when the driving IC 200 is viewed from the long side 204 side in a side view, the plurality of bump electrodes 252b are disposed so that a sum of areas of regions, not overlapped with any of the plurality of bump electrodes 250b included in the electrode group 257, of the plurality of bump electrodes 252b included in the electrode group 258 is equal to or larger than a sum of areas of regions, overlapped with any of the plurality of bump electrodes 250b included in the electrode group 257, of the plurality of bump electrodes 252b included in the electrode group 258. According to Embodiment 2, in probe inspection of the driving IC 200, it is easier to bring a probe into contact with each of the plurality of bump electrodes 252a from the long side 202 side of the driving IC 200 and it is easier to bring the probe into contact with each of the plurality of bump electrodes 252b from the long side 204 side of the driving IC 200, than Embodiment 1.

It is desirable that an area of the region R1 is equal to or larger than an area of the region R2 for all of the bump electrodes 252a included in the electrode group 256 and all of the bump electrodes 252b included in the electrode group 258. According to such a disposition, since it is possible to visually check all portions equal to or more than half of each bump electrode 252a from the long side 202 side of the driving IC 200 and it is possible to visually check all portions equal to or more than half of each bump electrode 252b from the long side 204 side of the driving IC 200, it is easier to bring the probe into contact with all of the bump electrodes 252a and the bump electrodes 252b.

Further, as illustrated in FIG. 14, the plurality of bump electrodes 252 (252a and 252b) may be disposed so that all of a sum of areas of the regions R2 and a sum of areas of the regions R4 are zero. For example, in plan view of the driving IC 200, each of the bump electrodes 252a may be disposed

so that distances L1 and L2 which are distances between the nearest two bump electrodes 250a are equal to each other and each of the bump electrodes 252b may be disposed so that distances L3 and L4 which are distances between the nearest two bump electrodes 250b are equal to each other. According to such a disposition, it is further easier to bring the probe into contact with each of the plurality of bump electrodes 252 (252a and 252b).

In the present embodiment, as illustrated FIGS. 13 and 14, in plan view of the driving IC 200, for each of the plurality of bump electrodes 252a included in the electrode group 256, the imaginary straight line 262a intersected with the bump electrode 252a and the long side 202 and not intersected with any of the plurality of bump electrodes 250a included in the electrode group 255 exists (imaginary straight line 262a can be drawn). In the same manner, in plan view of the driving IC 200, for each of the plurality of bump electrodes 252b included in the electrode group 258, an imaginary straight line 262b intersected with the bump electrode 252b and the long side 204 and not intersected with any of the plurality of bump electrodes 250b included in the electrode group 257 exists (imaginary straight line 262b can be drawn). Then, in examples of FIGS. 13 and 14, in plan view of the driving IC 200, the imaginary straight line 262a for each of the bump electrodes 252a is not intersected with any other of the bump electrode 252a and any other of the imaginary straight line 262a, and the imaginary straight line 262b for each of the bump electrodes 252b is not intersected with any other of the bump electrode 252b and any other of the imaginary straight line 262b. Accordingly, the probe can be brought into contact with all of the bump electrodes 252a constituting the electrode group 256 along the imaginary straight line 262a from the long side 202 side of the driving IC 200 and can be brought into contact with all of the bump electrodes 252b constituting the electrode group 258 along the imaginary straight line 262b from the long side 204 side of the driving IC 200.

The head unit 2 of Embodiment 2 described above has the same effects as those of Embodiment 1. Further, in the head unit 2 of Embodiment 2, since a proportion of parts of the bump electrode 252 which can be visually checked without being blocked by the bump electrode 250 from the long sides 202 and 204 side of the driving IC 200 is high, it is easy to bring the probe into contact with each of the bump electrodes 252. According to the head unit 2 of Embodiment 2, after the bump electrodes 250 and 252 are provided on the driving IC 200, probe inspection of the driving IC 200 can be performed by bring the probe into contact with each of the bump electrodes 250 and by bring the probe into contact with each of the bump electrodes 252 disposed on an inside than the bump electrodes 250. Accordingly, since it is possible to detect an operation error of the driving IC 200 and connection error of the bump electrodes 250 and 252 before completion of the head unit 2 of Embodiment 2, it is possible to reduce fraction defective (improve yielding percentage) after completion of the head unit 2 and to realize cost reduction of the head unit 2.

In the same manner as the head unit 2 of Embodiment 1, for example, the head unit 2 of Embodiment 2 may be used for a business ink jet printer developed and designed on a premise of being used in an office or the like.

3. Modification Example

In each of the embodiments described above, as a signal transmitted from the upper surface side embedded wiring 150 (reinforcement wiring) to an input terminal of the

driving IC 200 via the bump electrode 252, a power supply voltage signal or the driving signals COM-A and COM-B is used, but the signal transmitted to the input terminal of the driving IC 200 via the bump electrode 252 is not limited thereto. Another signal transmitted through a long wiring in an inside of the driving IC 200, for example, the clock signal Sck may be used.

In addition, in each of the embodiments described above, although the resin layers 251 and 253, and the bump electrodes 250 and 252 are provided on a surface of the driving IC 200, it is not absolutely necessary to be provided on the surface of the driving IC 200 and the resin layers 251 and 253, and the bump electrodes 250 and 252 may be provided on the second surface 142 of the sealing plate 160. In this case, by disposing each of the bump electrodes 252 in the same manner as in each of the embodiments described above, it is possible to perform probe inspection of the sealing plate 160.

In addition, in each of the embodiments described above, although as a relay substrate which relays a driving signal from the driving IC 200 to the pressure chamber forming substrate 129, the sealing plate 160 is used, it is not absolutely necessary to use the relay substrate and the driving IC 200 may be configured to be directly connected to the pressure chamber forming substrate 129. In such a case, the invention may be applied to a case where the upper surface side embedded wiring 150 is provided on the pressure chamber forming substrate 129 (an example of "substrate"). In this case, the resin layers 251 and 253, and the bump electrodes 250 and 252 may be provided on the driving IC 200 or on the pressure chamber forming substrate 129.

In addition, in each of the embodiments described above, although the driving circuits 50-a and 50-b are provided in the head unit 2, the driving circuits 50-a and 50-b may be provided in the control unit 10.

4. Application Example

In each of the embodiments and the modification example described above, the liquid ejecting apparatus 1 is a print only machine, but the liquid ejecting apparatus 1 may be a multi-function printer including a copy function and a scanner function.

In addition, in each of the embodiments and the modification example described above, the liquid ejecting apparatus 1 is a fixed type device, but the liquid ejecting apparatus 1 may be a portable type device.

In addition, in each of the embodiments described above, as an example of the liquid ejecting apparatus 1 used for the head unit 2, the business ink jet printer is used, but the liquid ejecting apparatus 1 may be another ink jet printer required to have high speed printing and high accuracy printing.

For example, the head unit 2 may be used for a textile ink jet printer which performs printing on a fabric or sublimates and transfers an image printed on a medium and performs printing on the fabric. The textile ink jet printer is mainly used for a purpose of producing small quantities of various types and high speed on-demand supply of products, and is used for providing fabrics in accordance with customer needs.

FIG. 15 is a schematic perspective view illustrating an example of the liquid ejecting apparatus 1 as the textile ink jet printer. As illustrated in FIG. 15, the liquid ejecting apparatus 1 (textile ink jet printer) includes a tray 302 capable of supporting a recording target medium (fabric) and a transport unit 303 which is a moving mechanism of the

tray 302. For example, a user puts on and sets a T-shirt to the tray 302 from a hem portion side of the T-shirt in a setting direction A1 so that a portion of the T-shirt desired to be recorded is positioned on an upper surface of the tray 302. The transport unit 303 transports a recording target medium supported by the tray 302 in a transport direction A (the setting direction A1 and a direction A2 opposite to the setting direction A1). The head unit 2 (not illustrated) is provided on an inside of a main body of the liquid ejecting apparatus 1. While reciprocating the head unit 2 in a direction B intersecting the transport direction A of the recording target medium, the liquid ejecting apparatus 1 causes the head unit 2 to eject an ink to the recording target medium supported and transported by the tray 302 to form a desired image.

In addition, for example, the head unit 2 may be used for a label ink jet printer which prints a receipt, a product label, a ticket, and the like. The label ink jet printer is mainly used in a supermarket cash register in cooperation with a POS system, an airport counter, a factory which performs printing of a package label of grocery, and the like and is required to print large volumes of data of different format at high speed, to operate stably, and the like.

FIG. 16 is a schematic perspective view illustrating an example of the liquid ejecting apparatus 1 as the label ink jet printer. The liquid ejecting apparatus 1 (label ink jet printer) illustrated in FIG. 16 includes a case 402 having a rectangular parallelepiped shape. A label issue port 403 (outlet) is formed on an upper side of a front surface of the case 402 and a mount outlet 404 is formed on a lower side of the label issue port 403. In addition, a paper feed button 405 and a plurality of LED lamps 406 for notifying an operation state and the like are disposed on a front surface of the liquid ejecting apparatus 1. A roll paper loading unit (not illustrated) is formed on an inside of the case 402 and a roll paper (not illustrated) having a configuration in which a roll is loaded in a roll shape in the roll paper loading unit. The roll paper is configured by sticking a plurality of labels 413 detachably at regular intervals on one surface side of an elongated mount 412 having a fixed width. In addition, the head unit 2 (not illustrated) which performs predetermined printing on the label 413 of the roll paper and a transport mechanism which transports the roll paper are disposed in an inside of the case 402. Then, by various types of mechanisms (not illustrated) provided on the inside of the case 402, the printed label 413 stuck to a surface of the mount 412 is detached from the mount 412 and is issued from the label issue port 403, and the mount 412 is discharged from the mount outlet 404.

In addition, for example, the head unit 2 may be used in an industrial ink jet printer (manufacturing apparatus) used for manufacturing an organic electro-luminescence (OEL) device, a color filter for a liquid crystal, or the like by a droplet ejecting method. The industrial ink jet printer is mainly used for manufacturing industrial products such as a liquid crystal color filter and an organic electro-luminescence device, and the like and is required to have ejection weight accuracy, enlargement to improve productivity, downsizing for improvement in concentration of finished products (high resolution of an ejecting unit), or the like.

FIG. 17 is a schematic perspective view illustrating an example of the liquid ejecting apparatus 1 as an industrial ink jet printer. The liquid ejecting apparatus 1 (industrial ink jet printer) illustrated in FIG. 17 includes a base 509, a stage 507 which is provided on the base 509 and supports a substrate 5 for an electroluminescent device, a Y axis direction driving motor 503 which drives the stage 507 on

the base 509 in the Y axis direction, a Y axis direction guide shaft 505 which guides a movement of the stage 507 in the Y axis direction, the head unit 2 which ejects a liquid material on the substrate 5 supported by the stage 507, an X axis direction driving motor 502 which drives the head unit 2 in the X axis direction, an X axis direction guide shaft 504 which guides a movement of the head unit 2 in the X axis direction, a cleaning mechanism 508, and a control device 510 which controls operation of the liquid ejecting apparatus 1. The stage 507 supports the substrate 5 and includes a fixing mechanism (not illustrated) for fixing the substrate 5 at a reference position. The Y axis direction guide shaft 505 is fixed so as not to move with respect to the base 509. The Y axis direction driving motor 503 is a stepping motor or the like. When a driving signal in the Y axis direction is supplied from the control device 510, the Y axis direction driving motor 503 moves the stage 507 in the Y axis direction. The cleaning mechanism 508 cleans the head unit 2. The cleaning mechanism 508 includes a driving motor (not illustrated) in the Y axis direction. The driving motor in the Y axis direction drives the cleaning mechanism 508 and the cleaning mechanism 508 is moved along the Y axis direction guide shaft 505. The control device 510 also controls a movement of the cleaning mechanism 508. The control device 510 supplies a signal for ejecting a droplet to the head unit 2. In addition, a driving pulse signal for controlling a movement of the head unit 2 in the X axis direction is supplied to the X axis direction driving motor 502 and a driving pulse signal for controlling a movement of the stage 507 in the Y axis direction is supplied to the Y axis direction driving motor 503. The X axis direction driving motor 502 is a stepping motor or the like. When a driving signal in the X axis direction is supplied from the control device 510, the X axis direction driving motor 502 rotates the X axis direction guide shaft 504. When the X axis direction guide shaft 504 is rotated, the head unit 2 is moved in the X axis direction. A droplet of a liquid material is ejected from a nozzle of the head unit 2 on the substrate 5 supported by the stage 507. This liquid material includes a material for forming an organic layer including a light emitting layer on the substrate 5. Then, by ejecting a droplet while moving the head unit 2, the substrate 5 for an electroluminescent device is manufactured.

In addition, in each of the embodiments and the modification example, the head unit 2 (printer head) for driving a piezoelectric element is described as an example, but the head unit according to the invention is not limited thereto. The invention can be applied to a device having a similar structure manufactured using MEMS technology, for example, a liquid crystal driving device, a liquid crystal manufacturing device, a MEMS sensor, and the like and the same effect is also obtained by such applications.

The present embodiment, the modification example, and the application example are described above, but the invention is not limited to the present embodiment, the modification example, and the application example. The invention can be implemented in various modes without departing from a gist thereof. For example, it is also possible to appropriately combine each of the embodiments, the modification example, and the application example.

The invention includes substantially the same configuration as the configuration described in the embodiment (for example, a configuration having the same function, method and result or a configuration having the same object and effect). In addition, the invention includes a configuration in which non-essential parts of the configuration described in the embodiment are replaced. Further, the invention includes

27

a configuration which achieves the same operational effect as the configuration described in the embodiment or a configuration which can achieve the same object. In addition, the invention includes a configuration in which a known technology is added to the configuration described in the embodiment. 5

What is claimed is:

1. A head unit comprising:
a plurality of ejecting units that eject liquids;
a driving IC that drives the plurality of ejecting units;
a substrate;
a first electrode group that includes a plurality of electrodes connecting the driving IC and the substrate with each other; and
a second electrode group that includes a plurality of electrodes connecting the driving IC and the substrate with each other,
wherein the driving IC is a rectangular shape that has a first short side, a first long side, a second short side, and a second long side in plan view,
at least a part of each of the plurality of electrodes included in the first electrode group and each of the plurality of electrodes included in the second electrode group is provided on a surface of a resin layer extended in a direction from the first short side to the second short side,
the plurality of electrodes included in the first electrode group are disposed in parallel in a direction from the first short side to the second short side along the first long side,
the plurality of electrodes included in the second electrode group are disposed at positions closer to the first long side than the second long side and farther from the first long side than the plurality of electrodes included in the first electrode group, and
for each of the plurality of electrodes included in the second electrode group, an imaginary straight line intersected with the electrode and the first long side and not intersected with any of the plurality of electrodes included in the first electrode group exists in plan view of the driving IC.
2. The head unit according to claim 1,
wherein an output signal from the driving IC is transmitted to the substrate via each of the plurality of electrodes included in the first electrode group, and
an input signal to the driving IC is transmitted from the substrate via each of the plurality of electrodes included in the second electrode group.
3. The head unit according to claim 2,
wherein the output signal from the driving IC is a driving signal that drives each of the plurality of ejecting units.
4. The head unit according to claim 3,
wherein the input signal to the driving IC is an original signal of the driving signal.

28

5. The head unit according to claim 2,
wherein the input signal to the driving IC is a power supply voltage signal.
6. The head unit according to claim 1,
wherein a length of the first long side is equal to or larger than 10 times a length of the first short side.
7. The head unit according to claim 1,
wherein the plurality of electrodes included in the first electrode group and the plurality of electrodes included in the second electrode group are provided on a surface of the driving IC.
8. The head unit according to claim 1, that is used for an industrial ink jet printer.
9. The head unit according to claim 1, that is used for a textile ink jet printer.
10. The head unit according to claim 1, that is used for a label ink jet printer.
11. The head unit according to claim 1, that is used for a business ink jet printer.
12. A head unit comprising:
a plurality of ejecting units that eject liquids;
a driving IC that drives the plurality of ejecting units;
a substrate;
a first electrode group that includes a plurality of electrodes connecting the driving IC and the substrate with each other; and
a second electrode group that includes a plurality of electrodes connecting the driving IC and the substrate with each other,
wherein the driving IC is a rectangular shape that has a first short side, a first long side, a second short side, and a second long side in plan view,
at least a part of each of the plurality of electrodes included in the first electrode group and each of the plurality of electrodes included in the second electrode group is provided on a surface of a resin layer extended in a direction from the first short side to the second short side,
the plurality of electrodes included in the first electrode group are disposed in parallel in a direction from the first short side to the second short side along the first long side,
the plurality of electrodes included in the second electrode group are disposed at positions closer to the first long side than the second long side and farther from the first long side than the plurality of electrodes included in the first electrode group, and
a sum of areas of regions, not overlapped with any of the plurality of electrodes included in the first electrode group, of the plurality of electrodes included in the second electrode group is equal to or larger than a sum of areas of regions, overlapped with any of the plurality of electrodes included in the first electrode group, of the plurality of electrodes included in the second electrode group in plan view of the driving IC in a direction from the first short side to the second short side.
